CONDUCTOR BAR SPLICE AND METHOD OF MAKING THE SAME

Charles F. Lamb, Cleveland, N.C., assignor to Grinnell Corporation, Providence, R.I., a corporation of Delaware

Filed June 25, 1962, Ser. No. 204,873

3 Claims. (Cl. 287—2)

This invention relates to a conductor rod joint and more particularly to the joint structure and method of making the same for channel shaped electrical conductor members on overhead tracks.

In textile mills it has been found advantageous to utilize moving air blowers of a particular design to maintain certain of the textile machinery in a relatively lint-free condition. In most cases, these cleaners are mounted to travel on a continuous loop of overhead track. The cleaners are preferably electrically powered and must pick up this power in some manner. One prior well-known method of tapping power is from a trolley wire set adjacent to the track. Another manner of providing power is by the use of rigid conductor members fastened to the track itself. This latter arrangement is the one with which the present invention is concerned.

The operation of the cleaning device is simply obtained by having brushes engage the conductor members throughout the travel of the cleaner. It has been found most convenient to utilize conductor bars in place of trolley wires because of the advantages obtained when going around a curve. Heretofore one of the major problems arising from the use of such conductor bars has been the manner with which sections of these bars are fastened together longitudinally. It is necessary that the joint not only be firmly fastened but that it have good conductivity characteristics. One prevalent prior art fastening utilized two wedge shaped members which were driven together within the channel opening. Subsequent experience has shown that this particular fastening has not been satisfactory because constant vibration of the cleaner passing on the overhead track set up vibrations in the conductor bar which loosened the wedge members and eventually caused electrical arcing, and finally, separation of the joint.

The present invention meets the above recited needs and problems and in addition provides a joint which is more easily assembled in the course of constructing the entire cleaning installation. This is accomplished by utilizing a single insert member which is a flattened tube of a somewhat egg-shaped cross-sectional configuration slightly wider than the channel interior portion. The flattened tube may be formed from hollow circular tubing. The use of such an insert not only increases the strength of the joint structurally, but has been found to give a joint which even after extensive use has better electric conductive properties than the prior double wedge joint construction.

A better understanding of this invention will become apparent from a perusal of the following description and the accompanying drawing in which:

FIGURE 1 is an elevational view of a cleaner assembly showing a portion of track having conductor bars fastened thereto and a symbolic representation of the cleaner mounted thereon.

FIGURE 2 is a perspective view of a portion of a single conductor bar showing the completed joint construction.

FIGURE 3 is an end view of a portion of conductor bar

2

showing a transitional stage in the construction of this novel joint.

FIGURE 4 is a cross-sectional view of the finished joint taken along line 4—4 of FIG. 2.

FIGURE 5 is an elevational view of a prior art construction showing double wedge-shaped members utilized in fastening the rod member end to end.

Referring now in greater particularity to the drawings, the numeral 10 denotes a cleaner assembly mounted on a rail 11. Fastened to the side of the rail are bar conductors 12 which are mounted on insulating members 14 in such a manner that the motors on the cleaning device 10 may pick up their electricity through brushes which are not shown.

In FIG. 2, a portion of the entire bar conductor is shown which contains one of the novel joints. The conductor is normally made up of a channel shaped member having two legs 20 and 21 and a rear wall or web 22. The joint retention member 24 is shown in its installed position. The joint is normally formed by pressing a length of flattened tubing slightly larger than the inside width of the channel member between the legs 20 and 21 so that the side walls of the flattened tube 24 frictionally engage the two bars to be joined. The length of this tubing will depend on the voltage to be carried by the bars, the expected intensity of the vibration set up by the moving cleaner, and the size of the bars. It is normally preferred that the flattened tubing have a slight taper to facilitate insertion between the legs 20 and 21 of the bars. However, this requirement is not mandatory. Insertion is usually accomplished by using a pair of wide jaw pliers or a hand vise having wide jaws such as shown in FIG. 4 at 26.

It will be seen that this joint is much easier to assemble than the prior art form shown in FIG. 5 which requires that two wedges be forcibly engaged in the same longitudinal direction as the bars. These wedges shown at 30 and 31 because of the large surface engagement often resist longitudinal movement so as to prevent a firm joint being formed between the bar members shown here at 32 and 33.

Having described a preferred embodiment of my invention, what I claim as new and seek to secure by Letters Patent is:

1. A splice for connecting the abutting ends of two similar conductor bars, each of said bars having two parallel extending flanges and a web perpendicular to and connecting said flanges, comprising a splice member having a hollow tubular shape with a cross-sectional configuration of substantially elliptical shape including flattened wall portion and extending longitudinally between the two parallel flanges of one of said bars and extending longitudinally between the parallel flanges of the abutting bar, a portion of the flattened walls of said member being in intimate retaining contact with the interior faces of the flanges of both bars for substantially the entire length of said member.

2. A splice for connecting the abutting ends of two similar conductor bars, each of said bars having two parallel extending flanges and a web perpendicular to and connecting said flanges comprising a splice member having a uniform hollow tubular shape with a cross-sectional configuration of substantially elliptical shape including flattened wall portions and extending longitudinally between the two parallel flanges of one of said bars and extending longitudinally for substantially an equal distance between the two parallel flanges of the abutting bar, a portion of

the flattened walls of said member being in intimate retaining contact with the interior faces of the flanges of both bars for substantially the entire length of said member.

3. A splice according to the recitation of claim 2 wherein the substantially elliptical cross-sectional shape of the splice member is slightly smaller in width at the interior of the conductor bars adjacent the web than the width of the member at the outer extremity of the flanges.
